UNITED STATES PATENT OFFICE.

FRANK S. WEAVER, OF MOUNDSVILLE, WEST VIRGINIA.

FLY-NET FOR HORSES.

SPECIFICATION forming part of Letters Patent No. 364,455, dated June 7, 1887.

Application filed February 7, 1887. Serial No. 226,776. (No model.)

To all whom it may concern:

Be it known that I, FRANK S. WEAVER, of Moundsville, in the county of Marshall and State of West Virginia, have invented a new and Improved Fly-Net for Horses and Method of Making the same, of which the following is a full, clear, and exact description.

My invention relates to fly-nets for horses, and has for its object to facilitate the production of inexpensive and durable goods of this character.

The invention consists in certain novel features of construction and combinations of parts of the fly-net and in the method of making the same, all as hereinafter fully described and claimed.

Reference is to be had to the accompanying drawings, forming a part of this specification, in which similar letters of reference indicate corresponding parts in all the figures.

Figure 1 is a plan view of part of a fly-net constructed in accordance with my invention. Fig. 2 is an enlarged detail view of part of one of the ribs or bars and with a spliced lash and a single lash fastened thereto, and shows also one of the slits made in the rib to receive the lash-fastening eyelets. Fig. 3 is a face view of part of one of the lashes, showing the slit therein for the passage of the eyelet-fastening. Fig. 4 is a longitudinal section on the line *x x*, Fig. 2; and Fig. 5 is a detail view illustrating how two lashes may be fastened together and how lashes may be spliced at one side of the intersecting joint.

In carrying out my invention I slit the fly-net lashes A and the net ribs or bars B at *a b*, respectively, where they are to intersect or cross each other, and then lay the lashes on top of the ribs and insert eyelets C through the slits *a b* and clinch them at the back or underside of the ribs, as clearly shown in the drawings.

Where a long lash crosses a rib of the net, as at the right-hand lash in Figs. 2 and 4 of the drawings, the eyelet will pass through but two thicknesses of leather or other material of which the net is made; but when a lash is to be joined or spliced the slit ends of its two parts will be lapped on each other over the slit of the rib or bar and the eyelet will be passed through all three thicknesses of mate-

rial and clinched at the under side of the rib, as shown at the left-hand lash in Figs. 2 and 4 of the drawings.

Fig. 5 illustrates how two narrow lashes, D 55 E, may be joined where they cross each other by the passage of an eyelet, C, through slits made in both lashes where they intersect, the back or clinched end of the eyelet being here shown; and this figure of the drawings also shows how 60 a lash may be spliced at one side of the intersecting joint by slitting the parts of the lash near their extremities, which are preferably pointed, as shown in full and dotted lines, and then passing the shank of the eyelet through 65 the slits of both parts, preparatory to upsetting or clinching the end of the eyelet for completing the fastening, this splice-joint clearly showing how the shank of the eyelet spreads the leather laterally in passing through the 70 slits in the lash.

It will be noticed that by simply slitting the lashes and ribs where the eyelet-shanks pass through them none of the material of the lashes or ribs of the net is removed; hence they retain quite or nearly their full strength, which is not the case when holes are punched through the lash or rib, or both, at their points of junction to receive fastening eyelets or rivets; hence the net is strong and durable, and the 75 lashes cannot slip or pull through their fastenings, as lashes held to net ribs or bars by the overlapping upon them of the end flanges of eyelets passed through the ribs at opposite edges of the lashes are liable to do; and this 80 latter method of fastening the lashes requires two eyelets at each intersecting joint in the net, materially increasing the cost of the fastenings and the labor in making the net over that required by my plan of slitting the lashes 85 and ribs and using a single eyelet at each joint, as above described. Furthermore, the methods of splicing the net-lashes either on the ribs or at one side of the joints or points of intersection allows the use of short strips in making 90 the lashes, thus utilizing material which otherwise would be of no value, and reducing the cost of the net.

Having thus described my invention, what I claim as new, and desire to secure by Letters 95 Patent, is—

1. As an improved article of manufacture,

a fly-net for horses, consisting of longitudinally-slitted ribs and lashes placed with their slits crossing each other, and rivets or eyelets passed through said crossed slits and clinched, substantially as set forth.

5 2. The herein-described method of uniting the ribs and lashes of fly-nets, which consists in slitting the ribs and lashes and then uniting

10 said parts by placing one upon the other with their slits crossing and then inserting an eyelet or rivet through the slits and clinching it, substantially as set forth.

FRANK S. WEAVER.
